UNITED STATES PATENT OFFICE.

FREDERICK H. HERHOLD, OF CHICAGO, ILLINOIS.

DESIGN FOR A BENT-STOCK CHAIR.

52,792.

Specification for Design. Patented Dec. 24, 1918.

Application filed January 7, 1918. Serial No. 210,784. Term of patent 14 years.

To all whom it may concern:

Be it known that I, FREDERICK H. HERHOLD, a citizen of the United States, residing at Chicago, county of Cook, and State of Illinois, have invented a new, original, and ornamental Design for Bent-Stock Chairs, of which the following is a specification, reference being had to the accompanying drawing, forming a part thereof.

The drawing is a perspective view of the chair showing my new design.

Copies of this patent may be obtained for five cents each, by addressing the "Commissioner of Patents, Washington, D. C."

I claim:

The ornamental design for a bent stock chair substantially as shown.

In testimony whereof I have hereunto signed my name in the presence of two subscribing witnesses.

FREDERICK H. HERHOLD.
